UNITED STATES PATENT OFFICE.

OLLIE BAUGHN, OF TOBIAS, NEBRASKA.

POTATO-PLANTING ATTACHMENT.

SPECIFICATION forming part of Letters Patent No. 398,119, dated February 19, 1889.

Application filed October 27, 1888. Serial No. 289,292. (No model.)

To all whom it may concern:

Be it known that I, OLLIE BAUGHN, a citizen of the United States, residing at Tobias, in the county of Saline and State of Nebraska, 5 have invented a new and useful Improvement in Potato-Planting Attachments, of which the following is a specification.

My invention relates to an improvement in potato-planting attachments for corn-planters; and it consists in the peculiar construction and combination of devices, that will be 10 more fully set forth hereinafter, and particularly pointed out in the claims.

The object of my invention is to provide an 15 attachment for corn-planting machines which shall be capable of cutting the potatoes and dropping the pieces thereof into hills at regular distances apart, and which shall be light and simple, strong and durable, and thoroughly reliable and efficient in operation.

In the accompanying drawings, Figure 1 is a perspective view of my potato attachment, showing the same attached to a corn-planter. Fig. 2 is a top plan view of the same. Fig. 3 20 is a vertical longitudinal sectional view of my improved potato-planting attachment, taken on the line $x x$ of Fig. 2. Fig. 4 is a sectional view taken on the line $y y$ of Fig. 2.

A represents the front cross-bar of a corn-planter of ordinary construction, having the usual runners, B, and provided with the usual hoppers, C, and the usual reciprocating seed-slide, D.

E represents a board, on the ends of which 35 are secured a pair of hoppers, F, the board constituting the bottoms of the hoppers, and being provided near its ends with discharge-openings G of suitable dimensions. The front and rear sides of the hoppers are 40 provided with longitudinal cleats H, arranged at a slight distance above the board E, and the end walls of the hoppers are provided in their lower sides with openings I.

K represents a reciprocating slide-bar, which 45 extends through the openings I, and is guided in the grooves formed between the cleats H and the bottom board, E, and said slide-bar is provided at each end with a pair of openings, L, adapted to alternately register with the 50 opening G, and arranged at a suitable distance apart. On the upper and lower sides

of the slide-bar, at the ends thereof, are secured plates M, which are made of steel or other suitable metal, and are provided with openings N, that register with the openings L. 55

O represents a pair of cutter-plates, which are arranged transversely in the hoppers, bear upon the upper side of the slide-bar, are over the openings G, and have their ends secured to the cleats H. The said cutter-plates have 60 their opposite sides provided with sharpened cutting-edges.

P represents a pair of metallic brackets, which are bolted to the outer ends of the corn-hoppers, project rearwardly therefrom, and 65 are also bolted to the outer ends of the potato-hoppers, and thereby support the potato attachment when the same is arranged on the corn-planter, as shown in Figs. 1 and 2. From the ends of the board E depend spouts R, the 70 upper ends of which register with the openings G, and the said spouts are secured to the corn-spouts S, which depend from the corn-hoppers, by means of U-shaped clip-bolts T. 75

The slide K may be operated by any suitable mechanism, such as are now commonly employed for reciprocating the seed-slide of a planter, said mechanism being not illustrated in this application, for the reason that it forms no part of my present improvement and is 80 well understood by persons skilled in this art.

The operation of this invention is as follows: The potatoes placed in the potato-hoppers drop into the openings L of the slide-bar K, and as the latter reciprocates are forced 85 against the cutting-edges of the cutter-plates O, and thereby cut into pieces of suitable size to be planted. As each opening L registers with the corresponding opening G, the cut piece of potato therein drops through the opening G into one of the potato-spouts and is 90 conveyed by the same to the ground, as will be readily understood.

Having thus described my invention, I claim—

1. In a potato-planter, the hoppers having the discharge-opening and the plates O, arranged above said opening, said plates being arranged transversely in the hopper and having their edges sharpened, in combination 100 with the reciprocating slide-bar K, having the openings L, adapted to register with the dis-

charge-opening of the hopper, and the plates M, secured on the upper and lower sides of said slide-bar, and having the openings N coincident with the openings L, substantially as 5 described.

2. A potato-planting attachment to corn-hoppers, comprising the board E, the hoppers F on the ends thereof, said board having the openings G in its ends, the spouts depending 10 from said board and registering with said openings, the cutter-plates O, arranged transversely in the hoppers above the openings G, the slide-bar K in the bottoms of the hoppers under the cutter-plates and having the open-

ings L, adapted to register with the openings 15 G, the bracket-arms adapted to be bolted to the hoppers F and to the corn-hoppers to secure the former in rear of the latter, and the clip-bolts to secure the spouts to the depending corn-spouts, substantially as described. 20

In testimony that I claim the foregoing as my own I have hereto affixed my signature in presence of two witnesses.

OLLIE BAUGHN.
